Primary Examiner — Michael C Stout*Assistant Examiner* — Nicole M. Leech(74) *Attorney, Agent, or Firm* — Leason Ellis LLP**(57) CLAIM**

The ornamental design for a mechanical connector for band, as shown and described.

DESCRIPTION

FIG. 1 is a front perspective view of a mechanical connector for band, showing our new design;

FIG. 2 is a rear perspective view thereof;

FIG. 3 is a front plan view thereof;

FIG. 4 is a back plan view thereof;

FIG. 5 is a right side view thereof;

FIG. 6 is a left side view thereof;

FIG. 7 is a top plan view thereof; and,

FIG. 8 is a bottom plan view thereof.

The broken lines in the drawings represent portions of the mechanical connector for band and form no part of the claimed design.
